Frederick S. Duncan, ATTORNEY.

UNITED STATES PATENT OFFICE.

HENRY L. GRASMUK, OF NEWARK, NEW JERSEY.

DESIGN FOR A LORGNETTE-CASE.

SPECIFICATION forming part of Design No. 35,292, dated November 19, 1901.

Application filed October 28, 1901. Serial No. 80,343. Term of patent 7 years.

To all whom it may concern:

Be it known that I, HENRY L. GRASMUK, a citizen of the United States, residing at Newark, in the county of Essex and State of New Jersey, have invented and produced a new and original Design for a Lorgnette-Case, of which the following is a specification, reference being had to the drawings accompanying and forming part of the same.

Figure 1 is a plan view of the outside face of the lorgnette-case. Fig. 2 is a transverse section taken on the line 2 2 of Fig. 1. Fig. 3 is a transverse section taken on the line 3 3 of Fig. 1.

The body A of the case has a general oval form and is joined with the spatulate handle C, there being slightly-indented portions at the juncture of these two parts. At the lower end of the handle is the compound oval end D E, formed by the crossing conventional leaf elements, which also form a border for the handle. The ring F is joined to the part E.

The head B, of general calyx formation, is joined to the body A.

The body of the lorgnette-case is ornamented by two dragons G, facing outward and arranged at either side of the body at the edge of the same. From the heads of the dragons runs the border element, which passes around the head B. The head B is also decorated by an inner band substantially parallel to the edge of the same, so that an inner panel is formed. The dragons on the body of the case are arranged so that a central shield-shaped panel is formed on the body of the case. On the handle near the juncture of the same with the body there is placed the satyr-head I.

What is claimed as new is—

The design for a lorgnette-case, substantially as shown and described.

HENRY L. GRASMUK.
